(57) **CLAIM**

The ornamental design for a dresser with a straight front, as shown and described.

DESCRIPTION

FIG. 1 is a front perspective view of a first embodiment of a dresser with a straight front showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right elevational view thereof;

FIG. 8 is a left elevational view thereof;

FIG. 9 is a front perspective view of a second embodiment of a dresser with a straight front showing our new design;

FIG. 10 is a rear perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right elevational view thereof;

FIG. 16 is a left elevational view thereof;

FIG. 17 is a front perspective view of a third embodiment of a dresser with a straight front showing our new design;

FIG. 18 is a rear perspective view thereof;

FIG. 19 is a front elevational view thereof;

FIG. 20 is a rear elevational view thereof;

FIG. 21 is a top plan view thereof;

FIG. 22 is a bottom plan view thereof;

FIG. 23 is a right elevational view thereof;

FIG. 24 is a left elevational view thereof;

(Continued)

FIG. 25 is a front perspective view of a fourth embodiment of a dresser with a straight front showing our new design; FIG. 26 is a rear perspective view thereof; FIG. 27 is a front elevational view thereof; FIG. 28 is a rear elevational view thereof; FIG. 29 is a top plan view thereof; FIG. 30 is a bottom plan view thereof; FIG. 31 is a right elevational view thereof; and, FIG. 32 is a left elevational view thereof. The broken lines show portions of the dresser with a straight front, which form no part of the claimed design.

1 Claim, 16 Drawing Sheets
